US00D621256S

(12) **United States Design Patent**
Andre et al.

(10) **Patent No.:** US D621,256 S
(45) **Date of Patent:** ** Aug. 10, 2010

(54) **PACKAGING**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, San Francisco, CA (US); **Matthew Dean Rohrbach**, San Francisco, CA (US); **Peter Russell-Clarke**, San Francisco, CA (US); **Douglas B. Satzger**, Menlo Park, CA (US); **Christopher J. Stringer**, Portola Valley, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/284,343**

(22) Filed: **Sep. 5, 2007**

(51) LOC (9) CL **09-03**

(52) U.S. CL **D9/432**

(58) **Field of Classification Search** D9/430–433, D9/414, 418, 420–423, 529, 560; 206/278, 206/297, 299, 433, 457, 770, 737, 769, 776, 206/777, 778, 320; 229/100, 101, 103.3, 229/106, 107, 108, 108.1, 109, 110, 112, 229/116, 116.5, 117, 117.01, 117.03–117.08, 229/121, 122, 122.24, 122.29, 125.015, 126, 229/152, 181.1, 185.1, 186, 201, 917, 922, 229/923, 930–933, 935, 937, 939, 942; 220/796

CLAIM

The ornamental design for packaging, as shown and described.

DESCRIPTION

FIG. 1 is a front perspective view of packaging showing our new design;

FIG. 2 is a front view thereof;
FIG. 3 is a side view thereof, the opposite side view being a mirror image thereof;
FIG. 4 is a bottom view thereof, the opposite side view being a mirror image thereof;
FIG. 5 is an exploded view thereof;
FIG. 6 is a front view of a base portion of the packaging of FIGS. 1-5;
FIG. 7 is rear view thereof;
FIG. 8 is a side view thereof, the opposite side view being a mirror image thereof;
FIG. 9 is a bottom view thereof, the opposite side view being a mirror image thereof;
FIG. 10 is a front view of another interior portion of the packaging of the design of FIGS. 1-5;
FIG. 11 is a bottom view thereof;
FIG. 12 is a side view thereof, the opposite side view being a mirror image thereof;
FIG. 13 is a bottom view thereof, the opposite side view being a mirror image thereof;
FIG. 14 is a perspective view of the lid and base of the packaging of FIGS. 1-5 in a closed condition with the interior portions removed for clarity of disclosure;
FIG. 15 is a front view thereof;
FIG. 16 is a side view thereof, the opposite side view being a mirror image thereof; and,
FIG. 17 is a bottom view thereof, the opposite side view being a mirror image thereof.
The broken lines in the Figures show environment which forms no part of the claimed design.
